UNITED STATES PATENT OFFICE

EDWARD FRIEDRICH, OF SAN ANTONIO, TEXAS.

DISPLAY-COUNTER.

1,108,985.

Specification of Letters Patent.

Patented Sept. 1, 1914.

Application filed November 1, 1913. Serial No. 798,649.

To all whom it may concern:

Be it known that I, EDWARD FRIEDRICH, a citizen of the United States, and a resident of San Antonio, in the county of Bexar and State of Texas, have invented a new and Improved Display-Counter, of which the following is a full, clear, and exact description.

My invention relates particularly to grocery counters having a series of drawers at the back thereof, and more especially to a novel form of sample containers, and means for supporting and removably retaining the sample containers at the front of the counter.

The invention will be particularly explained in the specific description following.

Reference is to be had to the accompanying drawings forming a part of this specification, in which similar characters of reference indicate corresponding parts in all the views.

Figure 1 is a front elevation of a counter having my improved sample containers and retaining means; Fig. 2 is a transverse vertical section; and Fig. 3 is a fragmentary horizontal section.

The counter 10 may be of any approved form having any desired number and arrangement of drawers 11. The counter has a closed vertical front 12, and supported on the front 12, about in line with the bottom of the drawers, are forwardly projecting shelves 13 which are of trapezoidal shape to present outwardly convergent sides. Said shelves are each adapted to receive and support a sample container 14, which will thus be positioned in front of each drawer 11.

The containers 14 are of glass to be transparent, and are trapezoidal in cross section to correspond with the shape of the supporting shelves 13. The upper ends of the containers are open, but may be provided with a movable closure or cover 14^a of any approved form to exclude the dust, here shown as simply a flat cover resting on top of the container. The height of the container with its cover is such as to be snugly received between two shelves 13.

In connection with the containers and their shelves I employ skeleton retaining frames, comprising vertical strips or side rails 15, 16 and connecting bars. The bars 55 are positioned to correspond with the posi-

tions of the shelves 13, and the intermediate bars numbered 17 are of a width considered vertically, to project above and below the intermediate shelves 13, while the lower cross bar 18 is of a width to project above the lower shelf 13, and the top cross bar 19 is of a width to extend below an element 13^a disposed on the counter above the top of the uppermost container 14.

Adjacent side strips 15 of a pair of skeleton frames are hinged to a fixed vertical member 20 on the counter, while the vertical strips or rails 16 at the free ends of each pair of frames are adapted to swing into a closed position adjacent to a fixed vertical strip 21 on the counter. Any suitable hinges 22 may be employed for hingedly securing the skeleton frames, and for locking the free ends of the two frames I may employ any known form of lock 23. The lock is conventionally indicated in Fig. 3, as being of that form of lock in which two bolts 24 may be projected or withdrawn at two opposite sides by any suitable key 25.

By the described construction the transparent containers 14 will afford a view of the samples *a* from the fronts and sides, and the containers are securely held against displacement by the skeleton frames. At the same time the said frames when swung open on their hinges will afford ready access to the containers for renewing their contents or for any other attention that they may require. The cross bars 17, it will be noted, conform to the shape of the trapezoidal containers, and the overlapping of the containers, both at the upper and lower ends of the latter, properly retains the containers in position. The side rails 15, 16, of the skeleton frames are beveled at their inner sides, so that they also conform to the sides of the containers, and their closing against the outer surfaces of the trapezoidal containers results in an effective clamping action on the latter. The swinging open of the skeleton frames will remove all obstruction from in front of the shelves for the convenient placing or removal of the containers. The bulging character of the attachment improves the appearance of the counter, results in an effective display of the samples, and affords convenient access to the containers when required.

Having thus described my invention, I claim as new and desire to secure by Letters Patent:

1. In a counter, a sample display attachment comprising a series of horizontal shelves, projecting forwardly at the front of the counter and of trapezoidal shape, a series of transparent containers trapezoidal in cross section, and a hinged skeleton frame 10 comprising vertical side rails beveled at their inner faces to conform to the conformation of the containers at the sides, and cross bars extending between the side rails in positions corresponding with the shelves, the 15 cross bars being of a width considered vertically to extend beyond the shelves and overlap the containers, and means for fastening the skeleton frame in closed position.
2. In a sample display attachment for 20 counters, a series of shelves projecting forwardly from the front of the counter, a vertical series of transparent sample containers of a height to fit between adjacent shelves, there being a member on the counter to extend over the uppermost container, the sides 25 of the shelves and containers being convergent in a forward direction, and a skeleton frame composed of vertical side rails and cross bars, the frame being hinged at one 30 side to the counter, the cross bars being positioned to correspond with the positions of the shelves and conforming to the sides and front of the shelves and containers and being of a width vertically to overlap the containers.
3. In a sample display attachment for 35

counters, a vertical series of shelves projecting forwardly from the front of the counter and each presenting side edges and a front edge, a series of transparent containers fitting between the shelves, and a skeleton retaining frame hinged at one side to the counter and having cross bars corresponding to the positions of the shelves, said cross bars in the closed positions overlapping the 40 containers.

4. In a sample display attachment for 45 counters, a vertical series of shelves projecting forwardly from the front of the counter, a transparent container on each of said 50 shelves, and a skeleton retaining frame common to the containers and shelves and serving to lock said containers in place on the shelves.

5. In a counter, a sample display attachment, comprising shelves projecting forwardly from the front of the counter, bulging containers on said shelves, and a skeleton retaining frame having cross bars 55 corresponding with the bulging containers, 60 said cross bars being positioned to correspond with the position of the shelves and overlap the containers, to lock the same in place.

In testimony whereof I have signed my name to this specification in the presence of two subscribing witnesses.

EDWARD FRIEDRICH.
